[57] CLAIM

The ornamental design for a set of bicycle reflector panels, as shown and described.

DESCRIPTION

FIG. 1 is a right side elevation view of a set of bicycle reflector panels showing our new design mounted on a bicycle which is shown in broken lines for illustrative purposes only;

FIG. 2 is a front elevation view thereof;

FIG. 3 is a top plan view thereof;

FIG. 4 is a bottom plan view thereof;

FIG. 5 is a rear elevation view thereof;

FIG. 6 is a left side elevation view thereof; and

FIG. 7 is an enlarged sectional view thereof taken along line 7—7 in FIG. 1 showing the set of panels separate from the bicycle.
